UNITED STATES PATENT OFFICE.

WILLY GÖSMANN, OF HANNOVER, GERMANY.

BURNER.

Application filed August 17, 1921. Serial No. 493,073.

(GRANTED UNDER THE PROVISIONS OF THE ACT OF MARCH 3, 1921, 41 STAT. L. 1313.)

To all whom it may concern:

Be it known that I, WILLY GÖSMANN, a citizen of Germany, residing at Hannover, Germany, have invented certain new and 5 useful Improvements in Burners (for which I have filed an application in Germany August 3, 1920), of which the following is a specification.

My invention relates to burners and more 10 especially to a device for insertion into the mixing tube of a Bunsen gas burner and its object is to reduce the consumption of gas, particularly of gas for heating purposes by effecting a more complete combustion of the gas.

According to the present invention this 15 reduction of the gas consumption is attained by thoroughly mixing the gas with the air of combustion by means of a nozzle-like device inserted in the mixing tube or chamber.

It has already been proposed to insert 20 into the mixing tube of gas burners twisted flat springs, which could be expanded, wire-gauze sieves and spirals of wire, which 25 taper towards the burner and which were put directly on the nozzle for the gas, where they act as non-return valves. These devices, however, only served the purpose of preventing back-firing.

The device according to my invention 30 consists of a wire coil, the windings of which are gradually reduced in diameter and form a truncated cone. The windings may be 35 located so close together that they form a closed mantle with spirally corrugated surface. If the spirals are wound with a clearance between them, the gas and air mixture can escape between them to the outside of 40 the coil, whereby throttling of the mixture is effectively avoided. Furthermore the flexibility of the coil is increased and the introduction of the device into the mixing tube through the air inlet is greatly facilitated. Some gas stoves do not possess an 45 air inlet suitable for the introduction of this supplementary nozzle and in this case it is necessary to introduce it from the burner end, which is only possible with a spiral 50 having spaced windings.

In a preferred form the wire at the rear end of the spiral is drawn straight out and protrudes from the mixing tube, where it is formed into a handle, which facilitates the removal of the device. The handle further enables the coil to be properly adjusted within the mixing tube. It is advantageous to push it nearer the burner in case of high gas pressure and to pull it towards the gas nozzle in case of low gas pressure 55 and thus in the latter case to increase the effect of the nozzle in sucking air into the mixing tube.

In a coil with close windings a disc of wire gauze such as commonly employed for 60 the prevention of back-firing, may easily be fixed between the windings and as the device may easily be withdrawn by means of the handle the cleaning of the coil and the sieve is greatly facilitated.

In the drawings affixed to this specification and forming part thereto a burner embodying my invention is shown by way of example.

Referring to the drawing, *a* is the mixing 65 tube or chamber, *b* the burner and *c* the gas nozzle. In the forward portion of the mixing tube or chamber *a* is disposed the conical wire coil or spiral *d*, which terminates in a straight extension *e*, projecting from 70 the tube *a* through the air inlet *f* and shaped into a handle *g*. Clamped between two turns of the spiral *d* is a wire-gauze sieve *h*.

When the mixture of gas and air passes 75 through the nozzle-like spiral or conical coil *d*, the currents are set into circular motion, whirled and thoroughly mixed together.

In the example illustrated a round wire 80 is shown, but the wire may have any other 85 cross-section, for instance rectangular, so that the current of gas and air impinges upon plane, spirally wound guide surfaces.

I wish it to be understood that I do not 90 desire to be limited to the exact details of 95 construction shown and described, for obvious modifications will occur to a person skilled in the art.

I claim:

1. In a device of the kind described in 100

combination, a burner tube, a closely wound wire spiral forming a truncated cone and a handle extending in parallel to the axis from the base thereof.

handle extending in parallel to the axis from the base thereof, and a sieve inserted between two windings of said spiral.

5 2. In a device of the kind described in combination, a burner tube, a closely wound wire spiral forming a truncated cone, a

In testimony whereof I affix my signature.

WILLY GÖSMANN.
